tion of the body adjacent the throat to limit the upward movement.

The mechanism for providing the rear legs with a progressive up and down movement is conventional. It includes a roller 12 mounted on a pin 13 which is carried by the legs and extends between them as shown in Fig. 5. The roller 12 is adapted to engage the periphery of the wheel 4 with the result that the rotation of the wheel 4 and recurrent rise and fall of the periphery thereof serves to raise and lower the rear legs 3.

One of the distinctive features of this improved toy animal is the location of the tail 7 which is shown in the drawings as a tail of a rabbit and which is mounted on and carried by the rear portion of the legs. As shown in Figs. 1 and 2, the tail 7 extends between projections from the rear legs 3 and extends across the width of the space between the rear legs, as shown in Fig. 2.

In the customary handling of the toy of this invention it may be pulled by means of a string or pushed by hand. As explained hereinbefore the rotation of the wheel 4 serves to raise the hind legs. The eccentric mounting of the wheel 4 likewise provides the rear portion of the body with an up and down movement suggestive of running. In Fig. 1 it will be observed that the forelegs are substantially in their lowermost position and the hind legs are approximately in their lowermost position. However, in Fig. 3 it will be noted that the forward end of the hind legs have been raised and have moved past the adjacent end of the element 6 as result of which an impulse has been transmitted to the forelegs 2 which are also shown in a slightly elevated position. Thus, the position of the legs as shown in Fig. 3,

in contrast to the position shown in Fig. 1, is highly suggestive of the jumping movement of a rabbit. The element 6 may be actuated by the front end of the hind legs either on the upward movement of the hind legs or on the downward movement thereof.

I claim:

1. In an animal type of toy, a body, forelegs pivotally mounted on said body, rear legs pivotally mounted on said body, wheels connected to said body to insure an upright position, a wheel eccentrically mounted adjacent the rear legs whereby rotation provides the rear part of said body and said rear legs with recurrent up and down movement as the toy is moved progressively forward and the forward end of said legs are moved up and down to a greater degree than the rear portion thereof, and means between said first mentioned wheels and movable with said body and pivotally mounted with respect thereto for moving said forelegs and adapted to be engaged by said rear legs to actuate said forelegs.

2. In an animal type of toy, a body, forelegs pivotally mounted on said body, rear legs pivotally mounted on said body, laterally positioned wheels one each positioned at opposite sides of said body, an axle on which said wheels are mounted, a rear wheel eccentrically mounted on said body whereby rotation of the wheel provides the rear part of said body and said rear legs with recurrent up and down movement as the toy is moved progressively forward, and means mounted on said axle for moving said forelegs and adapted to be engaged by said rear legs to engage and actuate said forelegs.

IRVIN W. FISHEL.
